UNITED STATES PATENT OFFICE.

JOHN FRANKLIN MACINDOE, OF PHILADELPHIA, PENNSYLVANIA.

LUBRICATOR.

1,026,961.

Specification of Letters Patent.

Patented May 21, 1912.

Application filed December 20, 1910. Serial No. 598,306.

To all whom it may concern:

Be it known that I, JOHN FRANKLIN MACINDOE, a citizen of the United States, residing at Philadelphia, in the county of Philadelphia and State of Pennsylvania, have invented certain new and useful Improvements in Lubricators, of which the following is a specification.

This invention embodies improvements in 10 elevator guide lubricators of the type set forth in my Letters Patent, #905724, issued Dec. 1, 1908, and in my allowed application for patent, Serial #553534, filed April 5, 1910.

15 The present invention resides particularly in the peculiar mounting of the distributers, whereby the lubricant is applied directly to the guide rails of the elevator, and also in certain details of construction increasing the 20 range of application of the invention under practical conditions of service.

For a full comprehension of the advantages and construction of the invention reference is to be had to the following detail 25 description and the accompanying drawings, in the latter of which—

Figure 1 is a perspective view of a lubricating device, embodying the essential features of the present invention; Fig. 2 is a 30 top plan view showing the arrangement of certain parts illustrated in Fig. 1, the central distributer, however, being a modified construction and Fig. 3 is a longitudinal section of the frame or body of the lubricator 35 bringing out more clearly the mounting of the central distributer.

As in the constructions of my previous lubricators hereinbefore referred to, a suitable compression cup 1 is mounted upon a 40 frame or body 2 of hollow construction, said frame being formed with an offstanding hollow arm 3 which supports a central distributer 4 arranged in a vertical plane intermediate those in which the side distributers are disposed. The distributers 5 are 45 supported by arms 6, and the latter are connected with the body or frame 2 of the device as shown at 7, at points on opposite sides of the arm 3.

50 The mounting of the distributers 5 is especially advantageous, since the arms 6 carrying the same are so connected with the body 2 of the device, at 7, so as to permit of a sort of swivel or rotative movement of the 55 arms with respect to the body 2. The arms 6 are tubular, preferably, so that they form

conduits to convey the lubricant from the body 2 to the distributers 5. As shown in Fig. 2, the arms 6 have one end passing through a wall of the body 2, and flared, as 60 shown at 6', to prevent their displacement. The arms 6 pass through stuffing boxes 8 secured to the body 2.

The arms 6 are offset intermediate of their ends to increase the extent of separating movement of the distributers 5 supported thereon. The distributers 5, of course, engage with opposite sides of the guide rail in the elevator shaft, and a coiled spring 9, or equivalent means, is connected 70 at its opposite ends with the arms 6 so as to normally exert a tendency to force said arms together for close frictional contact of the parts 5 with the elevator guide. In a manner similar to the connection of the inner 75 ends of the arms 6 with the body 2, the outer ends of the arms are connected with the distributers 5, and for such purpose said outer ends pass through stuffing boxes 8' and are flared at their inner extremities as are 80 shown at 6'' to afford the swivel or rotative mounting of the distributers 5 upon the arms. The distributers 5 are formed with distributing passages 5', as customary, and the tubular conduits afforded by the hollow 85 arms 6 communicate with the passages 5', from the latter of which the lubricant is carried direct to the surface of the elevator guide.

Referring to Fig. 3, it will be observed 90 that the central distributer 4 is provided at its outer end with the distributing passage 4' and its inner end is formed with a downwardly projecting flange 10. A lubricant tube 11 is secured to the outer end of the 95 distributer 4, and is slidable in an opening in the outer end of the arm 3 of the body 2. A spring 12 of the coiled type encircles the tube 11 between the outer extremity of the part 3 and the inner side of the outer end 100 of the distributer 4, and normally tends to force said distributer in an outward direction in yielding contact with the inner face of the elevator guide. To normally prevent displacement of the distributer 4, a stop 105 12' is provided in the form of an integral projection on the part 3, and with which the flange 10 is adapted to abut to limit the outward movement of the distributer 4 at its inner end. The lubricant tube 11 has 110 side apertures 13 which afford entrances for the lubricant into said tube. These aper-

tures 13 are regulated by means of a regulating screw 14 mounted in the inner end of the tube 11 and movable longitudinally in the latter to either partially or fully close 5 the apertures 13. The adjustable regulating screw 14 insures the adjustment to effect an equal distribution of the grease or lubricant, and to compensate for the increased resistance to the side distributers, in 10 the operation of the invention.

Referring to Fig. 2, the central distributer 15 is substantially the same structure as the distributer 4 hereinbefore described, excepting that the head 16 at the outer end of the 15 distributer, and which is provided with the lubricant supply passage, is transversely elongated and designed to lubricate an elevator guide of greater width than would be lubricated by the distributer 4.

20 The mounting of the rotative arms 6 and the similarly mounted distributers 5 are advantageous in affording a wide range of relative motion of the latter to accommodate application of the invention to elevator 25 guides of almost any size, without adjustment of said arms other than to arrange the same at opposite sides of the guide. Furthermore, the mounting of the parts 5 and 6 is advantageous in reference to the peculiar 30 movements which they are adapted to make in order that the distributing faces of the parts 5 may be kept against the guide rail, irrespective of the swing of the side arms 6, or the lateral motion of the car.

35 The means controlling the passage of the lubricant from the body 2 to the distributer 4, comprising the adjustable member 14 and the apertures or grease inlets 13, is of important advantage, in that the inlets 13 are 40 arranged substantially at a right angle to the direction of flow of the lubricant from the part 2 to the tube 11. Were the inlets 13 in line with the above direction of flow of the lubricant, they would also be in line 45 with the direction of movement of the tube 11 as the tube 11 reciprocates back and forth while operating in contact with the guide rail. Were the inlets 13 not arranged at a right angle to the direction of movement of the 50 part 11, the lubricant would not be supplied steadily and only as needed by the distributer 4, for the reason that inward movement of the tube 11 toward the body 2 would force an abnormal quantity of the 55 lubricant outwardly in the tube 11. On the other hand, the inlets 13 being located at

one or opposite sides of the tube 11, are so arranged that the lubricant will not enter the tube 11 on an inward movement of said tube, any more than it will enter the tube 60 under normal conditions while the latter might be stationary.

The arrangement of the inlets 13 is necessary to control the feeding of the lubricant to the distributer 4 in a constant manner and 65 only under the normal pressure in the grease cup 1. The adjustable screw 14 balances and controls more than one flow or inlet for the lubricant.

Having thus fully described my invention, 70 what is claimed as new is:—

1. In an elevator guide lubricator, the combination of a body, arms rotatively mounted thereon, distributers rotatively connected with said arms, and a resilient 75 connection between the arms.

2. In an elevator guide lubricator, the combination of a body, a lubricant supply means therefor, spaced arms rotatively mounted on the body and offset intermediate 80 their ends, a resilient connection between said arms, and lubricant distributers carried by the outer ends of the arms.

3. In an elevator guide lubricator, the combination of a hollow body, lubricant 85 supply means therefor, tubular arms rotatively connected at one end with the body, distributers rotatively mounted upon the outer ends of the arms, said arms being offset intermediate their ends, and a resilient 90 connection between the outer ends of the arms, the distributers having passages in communication with the tubular portions of said arms.

4. In an elevator guide lubricator, the 95 combination of a body, means for supplying a lubricant thereto, a distributer, a tube adapted to supply the lubricant from the body to the distributer and reciprocally mounted on the body, said body being provided with lubricant inlets arranged at substantially a right angle to the direction of movement of the tube on the body, and an adjustable screw carried by the tube for regulating the operative size of the inlets. 100 105

In testimony whereof I affix my signature in presence of two witnesses.

JOHN FRANKLIN MACINDOE.
